UNITED STATES PATENT OFFICE.

JEROME H. INGRAHAM, OF KNOX CITY, TEXAS, ASSIGNOR OF ONE-HALF TO C. W. FULLIG, OF KNOX CITY, TEXAS.

HOT-AIR MIXER.

1,333,114.

Specification of Letters Patent. Patented Mar. 9, 1920.

Application filed January 21, 1919. Serial No. 272,389.

To all whom it may concern:

Be it known that I, JEROME H. INGRAHAM, a citizen of the United States of America, residing at Knox City, in the county of Knox and State of Texas, have invented certain new and useful Improvements in Hot-Air Mixers, of which the following is a specification, reference being had therein to the accompanying drawing.

10 This invention relates to a hot air mixer, that is used in connection with the gas engine of motor vehicles.

The object of my invention is the production of an efficient and novel device whereby 15 air is readily heated and delivered to the manifold of a gas engine at the will of the operator.

With this and other objects in view my invention consists of certain other constructions and arrangements of parts as will be more fully described hereinafter and set forth in the claims.

In the drawings:

Figure 1 is a view in side elevation of the 25 device constructed in accordance with my invention.

Fig. 2 is a top plan view of the device shown in Fig. 1.

Fig. 3 is a longitudinal sectional view of 30 the hot air chamber or cylinder.

Fig. 4 is an enlarged detail view of the 35 pedal device of my invention.

Fig. 5 is a vertical sectional view taken on line 5-5, Fig. 1, looking in the direction of 40 the arrows.

Referring to the drawings by numerals, 1 designates the motor and 2 the manifold thereof. The exhaust pipe 3 is connected to the motor in the usual manner, and upon the 45 exhaust pipe 3 is mounted a pair of clamps 4. Each clamp 4 is provided with an upper and lower cylindrical portion; the lower cylindrical portion of the clamp surrounding the exhaust pipe 3, and the upper cylindrical portion of the clamp surrounds the hot air mixing chamber or cylinder 5, more clearly seen upon referring to Fig. 5; each clamp is bent inwardly at 6, at its middle, holding the hot air chamber 5 slightly above 50 the exhaust pipe 3. It will be obvious by reason of the close positioning of the cylinder 5 to the exhaust pipe 3 that the cylinder 5 will be heated when the motor is in operation.

An intake valve 7 is carried by the cylinder 5, near its inner end, and the valve member therein is, through its stem 8, rotated, by a pedal device hereinafter described, for allowing entrance of air into the cylinder 5, by reason of a vacuum suction action through feed pipe 9, coupler 10, and the manifold.

The feed pipe 9 is detachably secured to the outer end of the cylinder 5 by means of a stuffing box 11 carried by the cap 12 of the outer end of the cylinder 5; the inner end of cylinder 5 is closed by a threaded cap 13. By removing cap 13 and intake valve 7, as well as cap 12 together with the stuffing box 11, the cylinder 5 can be removed from the upper rounded or loop portion of the clamps or bracket members 4.

My pedal device comprises a bracket 14 fixedly secured at 15 to the bottom 16 of the automobile. This bracket 14 is provided with a lug 17, to which lug is fastened spring 18. Pivoted at 19, upon the lower end of bracket 14, is bell crank lever 20; said lever 20 is provided with an upwardly extending lug 21, and engaging the lug 21 is 80 threaded bolt 22, which bolt 22 is carried by bracket 14 above the pivot 19. A locking nut 23 is mounted upon bolt 22 for locking the bolt in an adjusted position upon the bracket whereby the normal position of bell 85 crank lever 20 can be adjusted to a nicety, so that the valve member of intake valve 7 will be retained in a position to cause its passages to register correctly; no claim is made to the specific structure of valve 7.

A rod 24 is pivotally connected at 25 to the arm 8 of the rotary valve member in the valve 7, and the opposite end of rod 24 is pivotally connected at 26 to the lower end of lever 20. A vertical movable plunger rod 27 is carried by the bottom 16 of the machine, and said plunger rod 27 is provided with a pin 28 working in an elongated aperture 29 formed near the outer end of lever 20. This pin 28 and aperture 29 allows sufficient play of the lever 20 and rod 27 to permit of the downward movement necessary to impart a swinging motion to rod or link 24 and arm 8 of valve 7 for opening or closing the valve member of valve 7 100 as desired. On lever 20 is formed a lug 30, near aperture 29, and the lower end of spring 18 is fastened to lug 30, for nor-

mainly exerting an upward pull on the other end of the lever to hold the valve member in valve 7 in a closed position.

On rod 27, near its upper end, is formed 5 a lug 31 that is provided with an inclined beveled face over which rides the inner end of the latch pedal 32, this latch pedal 32 is carried by a lug 33; this lug 33 is fastened to the floor 16 of the machine. A spring 10 34 normally exerts an outward pressure on the latch pedal, holding the pedal over the lug 31 when the plunger rod is pressed downwardly, causing the lug 31 to ride under the inner end of the latch pedal 32, 15 shown in dotted lines, Fig. 4, when the latch pedal is pressed downwardly at its outer end, the plunger rod 27 will be released, and by reason of the strain exerted on the outer end of lever 20 and plunger rod 27, plunger rod 27 will move upwardly, and through the lever 20 and rod or link 24 the rotary valve member in the valve 7 will be closed.

From the foregoing it will be appreciated 25 that when the operator of the machine desires to cause hot air to be passed into the manifold of the motor, for facilitating the running of said motor, all he has to do is to press down on the plunger rod 27 thereby 30 opening the intake valve 7 and allowing air to enter the hot air cylinder 5 whence, the suction or a vacuum action caused by the motor running, will cause the heated air to be drawn into the manifold and thence into 35 the cylinders of the motor.

What I claim is:—

1. In a device of the class described, the combination with a motor provided with a manifold and an exhaust pipe, of a hot 40 air cylinder positioned above said exhaust pipe, means spacing said hot air cylinder from said exhaust pipe, means detachably connecting one end of said cylinder to said manifold, an intake valve carried by said cylinder, said intake valve provided with 45 a rotary member having an arm, a rod

connected to said arm, a pedal device comprising a bracket, a bell crank lever pivotally mounted upon said bracket, said rod pivotally connected to one end of said lever, a plunger rod, a pin on said plunger rod, said lever provided with an elongated slot, said pin working in said slot, a spring attached to one end of the bracket and at its opposite end to said lever, and means for temporary holding said plunger rod and lever in an adjusted position. 50

2. In a device of the class described, the combination with an exhaust pipe and a manifold, means provided with an intake valve positioned contiguous to said exhaust pipe and communicating with said manifold, of a pedal device for actuating said intake valve comprising a bracket provided with an apertured lower end and 60 with an apertured lug extending therefrom near its upper end, a bell crank lever pivotally mounted upon the lower end of the bracket, a rod pivotally connecting said lever to said intake valve, said lever provided near its pivot with an upwardly extending lug, a threaded bolt carried by said bracket and engaging said last-mentioned lug, a lock nut on said bolt and engaging the bracket, said lever provided near one 65 end with an elongated aperture and with a second lug, a spring attached to the lug of the bracket and to the second-mentioned lug of the lever, a vertical movable plunger rod provided near its upper end with a lug 70 having an under beveled face, and said rod provided near its lower end with a pin, said pin working in the elongated aperture of said lever, a latch pedal adapted to engage the beveled face of the lug on 75 the rod and ride over the same and lock the rod in an adjusted position, and a spring exerting an upward pressure upon the latch near its outer end. 80

In testimony whereof I hereunto affix 85 my signature.

JEROME H. INGRAHAM.
